UNITED STATES PATENT OFFICE

2,516,801

CHAIR HAVING SPRING SUPPORTED SEAT

Harold E. Renaud, Lansing, Mich.

Application March 16, 1944, Serial No. 526,695.

3 Claims. (Cl. 155—52)

1

This invention relates to chairs and more particularly to a combination chair suitable for use optionally either as a high chair or baby bouncing chair or simultaneously as both.

The present application is a continuation in part of my copending application Serial No. 360,833, filed October 11, 1940, for Child's High Chair, which has become abandoned.

The principal objects of the invention are to provide such a chair which is mechanically efficient, safe, sturdy, simple of construction, inexpensive, which can be quickly and easily assembled and disassembled, and which when disassembled is composed of parts which can be conveniently packaged in a compact package for transportation.

The foregoing and other objects are attained by the novel construction and arrangement of the several parts of a chair embodying the present invention, examples of which are shown in the accompanying drawings, wherein:

Figure 1 is a side view in elevation of a chair illustrating a preferred embodiment;

Figure 2 is a fragmentary front elevational view of the chair shown in Figure 1;

Figure 3 is a fragmentary view of the tray locking mechanism shown in Figure 2 and taken on the line 3—3 of that figure;

Figure 4 is an enlarged fragmentary view, partly in section, of the tubular support and associated mechanism forming a part of the chair shown in Figure 1;

Figures 5, 6 and 7 are views similar to Figure 4 showing the tubular supports and associated mechanism in various positions encountered in use of the chair;

Figures 8 and 9 are enlarged side views partly in section of the upper part of the supporting tubes and associated mechanism for locking the parts against vertical movement, Figure 8 showing the mechanism in non-locking position, and Figure 9 showing the mechanism in locking position;

Figure 10 is a fragmentary side elevational view showing the operating handle and associated connections for the locking mechanism of Figures 8 and 9;

Figures 11 and 12 are fragmentary vertical and longitudinal sectional views, respectively, of an alternative form of locking mechanism which may be substituted for the mechanism shown in Figures 8 and 9;

Figure 13 is a horizontal sectional view taken on the line 13—13 of Figure 1;

2

Figure 14 is a horizontal sectional view taken on the line 14—14 of Figure 1;

Figure 15 is a top plan view of the chair shown in Figure 1;

Figure 16 is a side elevational view of a chair illustrating an alternative embodiment of the invention; and

Figures 17, 18 and 19 are fragmentary elevational views, partly in section and on an enlarged scale, of the alternative embodiment shown in Figure 16.

The chair shown in Figure 1 includes: a seat portion generally designated by the reference numeral 10 which has secured to the bottom side thereof a downwardly extending seat tube 11; and a base portion generally designated by the reference numeral 12 having secured thereto an upstanding base tube 13. The seat tube 11 is telescopically received in the base tube 13 for vertical and rotatable movements relative thereto. As will be described more in detail presently, spring means are contained within the tubes 11 and 13 so that the seat 10 is yieldably supported from the base 12.

The base 12 comprises four legs 14, 15, 16 and 17, which are secured to what may be termed hub plates 18 and 19 in a novel manner. The two legs 14 and 16 are permanently secured to the lower plate 19 and the two legs 15 and 17 are permanently secured to the upper plate 18, to form pairs. When assembled as shown in Figure 1, the plates 18 and 19, which are provided with openings for that purpose, surround the base tube 13 and are secured together in overlapping relationship by bolt and nut assemblies. This particular arrangement of parts (the securing of pairs of legs to separate hub plates) facilitates the packaging of the chair for shipment and the assembly of the chair after shipment.

The openings in the plates 18 and 19 are slightly larger than the outer diameter of the base tube 13 and the legs are connected to the base tube 13 to support the same, in the manner now to be described. Permanently secured to each of the four legs is an upstanding arm or bracket 21 formed at their upper extremities to be secured, as by the screws 22, to the under surface of a circular foot rest platform 23. The platform 23 has a central opening therethrough which receives the base tube 13. Permanently secured (as by welding) to the base tube 13 is an annular flange member 24 adapted to overlie the upper surface of platform 23. A clamping plate 25, which may be either loose or secured to the plat-

form 23 is provided to cooperate with the flange

24 to secure the platform to the base tube 13. Such securement is accomplished by means of the bolt and nut assemblies 26 which detachably connect the platform to the base tube. In other words, the sole connection between the base tube and the legs upon which it is supported is through the platform 23 and the flange and plate construction just described.

The seat 10 includes a seat proper 27 having the front edge thereof recessed as at 27a and 27b to receive the legs of an occupant of the chair. A back 28 is secured to the seat proper 27, and side arms 29 extend between the back and the front portion of the seat proper 27.

Slidably mounted upon the upper part of the arms 29 is a tray 30. Provision is made for locking the tray in any desired position through means of the locking mechanism illustrated generally in Figure 3.

The locking mechanism is identical on both sides of the chair and only one side is shown on Figure 3. As there shown, this mechanism includes an element 31 secured to the top of the upper branch of the arm 29 and having notches formed therein along the inner edge thereof adapted to cooperate with the ratchet element 32 carried by the tray 30. As shown, the ratchet element 32 is pivotally connected to a plate 33 which is in turn fastened to the bottom of the tray 30. Spring means 34 urges the ratchet element 32 toward the member 31 and into engagement with the teeth thereof. Provision is made for releasing the effect of the springs 34 through means of a rod 35 extending toward the center of the chair and supported from the tray 30 by a bracket 36. The rod 35 is formed to provide a handle 37 by means of which the ratchet element 32 may be released from the teeth of the element 31 to permit the adjustment of the tray in a conventional manner.

The seat tube 11 is detachably connected to the seat proper 27 by means of a flange 11a formed at the upper extremity of the tube. The flange is in turn secured to the under side of the seat proper 27 by means of screws 38.

From the description thus far it will be apparent that the tray 30 may be removed from the arms 29; that the seat 10 may be disconnected from the seat tube 11; that the platform 23 may be disconnected from the base tube 13; that the platform 23 may be disconnected from the upstanding arms 21 carried by the legs; and that the legs may be separated from each other in pairs. This particular arrangement of parts lends itself to ease of manufacture and assembly and convenient packing for shipping.

By forming the legs and the chair arms of tubular elements, the overall weight and the cost of fabrication of the chair are materially reduced.

It will also be apparent from the description thus far that the legs 14, 15, 16 and 17, which constitute the base proper, extend outwardly beyond the periphery of the platform 23 and that the outer periphery of the platform 23 is located radially outwardly of the outer perimeter of the seat 10. This also is an important feature of the construction and arrangement of parts. By this particular construction and arrangement of parts a pyramid type of structure is provided which affords protection against the accidental tipping over of the chair irrespective of how vigorous the activity of the occupant may be. This is especially important when it is remembered that the chair is adapted for use as a "bouncing" de-

vice, as will be described more in detail presently. The "bouncing" is made possible by reason of the spring means contained in the tubes 11 and 13.

5 The spring means which are contained within the tubes 11 and 13 and the associated mechanisms are shown in Figures 4 to 10 inclusive. Referring first to Figure 4, it will be observed that the tube 11 is formed with an enlarged portion at its lower extremity, the outer diameter of which approaches the internal diameter of the base tube 13, to provide for telescopic engagement therewith. The change in diameter of the seat tube 11 serves the dual purpose of providing interiorly of the tube a container for one of the springs to be described presently, and exteriorly of the tube a shoulder 39 adapted to be engaged by a screw 40 carried by the base tube 13, which locks the seat tube 11 to the base tube 13 and prevents the withdrawal of the former from the latter. This arrangement, of course, results in the upper portion of the seat tube 11 being of a reduced diameter, and when that portion is telescoped within the base tube 13, places it in spaced relation to the tube 13. This also is responsible for an advantageous result, namely, the prevention of contaminating either the exterior of the seat tube 11 or the base tube 13 by any lubricator which may be disposed within the tubes to provide for the free movement of the seat tube 11 within the base tube 13.

20 The lower extremity of base tube 13 is closed by a closure member 41 secured thereto which is provided with a central opening surrounded by an 35 interiorly threaded boss 42. An exteriorly threaded bolt 43 having secured to its lower extremity an operating handle 44 is received within the boss 42. At its upper extremity the bolt 43 has mounted thereon a cup-like member 45 adapted to receive the lower ends of two spring elements. The cup member 45 is held in position 40 by nut 46 threaded onto the upper end of the bolt 43. It will be understood that by rotating the bolt 43 the cup member 45 may be raised or lowered within the base tube 13.

50 The spring means contained within the tubes 11 and 13 includes three separate compression springs, designated by the reference numerals 47, 48 and 49. Spring 47 is a relatively weak spring and is designed to provide for yielding movement of the seat portion 10 of the chair even though the occupant of the chair is of but little weight. Spring 48 is a stiffer spring and comes into operation primarily when a heavier occupant is in the seat.

55 Springs 47 and 48 are separated from each other by a floating support 50 which is formed in the shape of a cylinder closed at one end and having a radial peripheral flange at the other end. Spring 47 surrounds the cylindrical side wall of the support 50 and is confined between the peripheral flange of that support and a horizontal wall at the shoulder 39 formed in tube 11. Spring 48 has its upper end disposed within the 60 cylindrical support 50 and is confined between the closed end of the cylindrical support 50 and the cup-like member 45 carried by adjusting bolt 43. The floating support 50, as its name implies, is capable of vertical movement within the larger end of seat tube 11 where it is confined at all times.

70 Spring 49 is the strongest of the three springs and is disposed within the spring 48, being coiled in the opposite direction so as to avoid interference. The upper end of spring 49 is disposed

well below the upper end of the spring 48 when the chair is unoccupied and the parts are in the position shown in Figure 4. Spring 49 serves to reinforce spring 48 when an extremely heavy load is placed upon the chair, but does not interfere with the normal flexing of spring 48 until the time that spring 49 comes into operation.

The positions of the springs 47 and 48 when compressed substantially to their extreme limits are shown in Figure 5.

Figures 6 and 7 illustrate the function of the adjusting bolt 43. Its purpose is to precompress the springs so as to maintain the desired relationship between the foot rest platform 23 and the seat proper 27 when heavier loads are imposed on the seat. It will be understood that when the several parts are in the positions shown in Figures 1 and 4 the platform 23 is spaced from the seat proper 27 a suitable distance to accommodate a very young child or one of relatively little weight. That is to say, the weight of such a child will cause considerable compression of spring 47 and some compression of spring 48, and seat proper 27 will be lowered sufficiently to make platform 23 a convenient rest for the child's feet.

Obviously, if a heavier child were seated in the chair his weight would depress the chair further and reduce the distance between the seat proper 27 and the platform 23, so that the platform 23 would not afford a convenient resting place for the child's feet. The adjustment available through the bolt 43 is designed to overcome this disadvantage.

It will be readily apparent that when the bolt 43 is threaded into the tube 13 that springs 47 and 48 will be precompressed so that a greater weight will be required to further compress the springs than would have been required had there been no precompression. The greater the amount of the precompression the greater the weight which will be required to effect a further compression.

The adjustment afforded through the adjusting bolt 43, as described above, provides a means for maintaining a proper relationship between the foot rest platform 23 and the seat proper 27. This might also be accomplished as is herein-after described by providing a platform which is adjustable vertically of the base tube 13.

By reference again to Figure 4 it will be observed that the exterior of the tube 11 is provided with weight measuring indicia. These are provided in order to take advantage of the weighing characteristics afforded by the use of the springs 47, 48 and 49. An indicator in the form of a cylinder 51 is disposed around the tube 11 and is supported from the operating handle 44 associated with the adjusting bolt 43. This is a novel feature of the present invention and makes possible the accurate measurement of the weight of an occupant of the chair even though the springs have been precompressed as previously described. The connection between the indicator 51 and the handle 44 includes a cylinder 52 seated within the confines of the handle and telescopically received around the exterior of the base tube 13. The cylinder 52 is provided with an outwardly extending peripheral flange 53 at its upper extremity to which are secured a plurality of connecting rods 54. The upper extremities of these connecting rods are secured to the outwardly extending peripheral flange 51a of indicating element 51.

From the foregoing description it will be un-

derstood that when a child is placed in the seat 10 and locked in position by the tray 30, that his legs will extend downwardly through the recesses 27a and 27b and that the springs 47 and 48 will be compressed sufficiently to permit his feet to rest upon the platform 23. By pushing against the platform 23 the child can impart a bouncing motion to the seat 10. It may be desirable during feeding periods or at other times to prevent the bouncing action of the seat. To that end provision is made for locking the seat 10 against bouncing or vertical movement in relation to the base 12. The mechanism for that purpose will now be described.

The preferred form of locking mechanism is shown in Figures 8 to 10, and an alternative form is shown in Figures 11 and 12.

As shown in Figure 8, the locking mechanism includes a pair of radially reciprocable lock pins 55 and 56 mounted in aligned openings at opposite sides of the seat tube 11 immediately above the shoulder 39. The pins are formed with a cooperative projection and recess as shown in Figure 8 with a compression spring 57 contained therein. The spring 57 tends to urge the locking pins radially outwardly to the position shown in Figure 9. In that position they extend outwardly over the upper extremity of base tube 13 and lock the seat 10 against downward vertical movement. Further upward vertical movement of the seat tube 11 in relation to the base tube 13 is prevented by the set screw 40 previously described in connection with Figure 4.

The construction and arrangement of the lock pins 55 and 56 is such as to permit them to be moved radially inwardly against the force of spring 57 to the position shown in Figure 8. In that position the lock pins 55 and 56 clear the upper extremity of base tube 13 and permit vertical reciprocation of the seat tube 11 within the base tube 13.

A novel operating mechanism is provided for conveniently actuating the lock pins 55 and 56 so as to move them either to their locking or their non-locking position. This mechanism comprises a cam member 58 which is generally in the form of an inverted cup and which is provided with cam surfaces 59 adapted to contact the cam surfaces 55a and 56a on the lock pins 55 and 56. Notches are formed in the cup member 58 to receive the pins while permitting the cam surfaces 59 to engage the cam surfaces 55a and 56a.

Cam member 58 is reciprocated vertically by a crank mechanism which includes the connecting rod 60 having its lower extremity secured to the cam member 58 and its upper extremity secured to a crank 61. Crank 61 extends through openings provided for that purpose in the seat tube 11 and has at one end thereof an operating handle 62. Adjacent the operating handle the shaft of crank 61 is rotatably supported from the bottom of the seat proper 27 by a bracket 63 secured to the seat 27 by screws 64. Adjacent its opposite extremity and located within the seat tube 11 the crank is provided with an arm or a lever 65 which, as shown in Figures 9 and 10, engages the bottom of seat 27 when the crank 61 is rotated to raise the cam member 58. In this manner the arm 65 serves as a stop to prevent rotating the crank beyond the upper position.

The locking mechanism which has just been described has two outstanding advantages. The major portion of the mechanism is wholly contained within the seat tube 11; and the operating handle for actuating the mechanism is disposed

at a position convenient for the use of anyone other than the occupant of the chair. Obviously, it is not desirable to have the operating mechanism arranged where it can be used by a child occupying the chair. On the other hand, it is desirable to have this mechanism arranged where it can be used by the attendant of the child seated in the chair.

It will be recognized that the locking mechanism described above is capable of locking the seat 10 only in its uppermost position. For most purposes this is the only position in which it would be desired to lock the chair against reciprocation. However, provision can be made for locking the chair in any desired position within the limits of the vertical movement of seat tube 11 within base tube 13. Mechanism for this purpose is illustrated in Figures 11 and 12.

As shown in Figure 11, the seat tube 11 is formed immediately above the shoulder 39 with a plurality of flanged openings 66 therein. Disposed within each of these openings and supported by the flanges surrounding the opening is a brake block 67 adapted to be pressed outwardly into engagement with the interior surface of base tube 13. When so pressed outwardly the brake blocks lock the tube 11 to the tube 13 in whatever position these tubes may be in at the time the brake blocks are pressed outwardly.

The mechanism for moving the brake blocks radially outwardly to locking position comprises a shaft 68 which may be a modification of the connecting rod 69 of Figures 8 and 9, and which may be operated by the same crank mechanism as shown in those figures. Secured to the lower end of shaft 68 is a wedge member 69 adapted to engage the cam surfaces of brake blocks 67 which are located on the radially inner surfaces thereof. By reference to Figure 11 it will be apparent that when the shaft 68 and the wedge member 69 are in the position there shown, namely, the lowermost position for the wedge member 69, the brake blocks 67 are spaced from the internal surface of the tube 13; and that when the shaft 68 and the wedge member 69 are moved upwardly the brake blocks 67 are forced radially outwardly into locking engagement with the inner surface of tube 13.

This alternative form of locking mechanism just described may be used when it is desired to lock the seat in any one of its various vertical positions.

A modified and somewhat simplified form of the invention is illustrated in Figures 16 to 19 inclusive. The chair shown in Figure 16 includes a seat 10 having secured to the under surface thereof a seat tube 71; a base in the form of a plurality of legs 72 secured together as a unit and supporting a base tube 13; and a foot rest platform 74 connected to the base tube 13 for vertical adjustment relative thereto.

Disposed within the tubes 71 and 13 is a coil compression spring 75 adapted to yieldably support the seat 10 from the base. The spring 75 is confined between a portion 76 of the legs 72 upon which the lower extremity of tube 13 rests and a shoulder 77 formed to extend inwardly into seat tube 71 near its lower extremity. Immediately above the shoulder 77 the seat tube 71 is formed to provide an outwardly extending shoulder 78 which thus forms an outwardly opening groove 79 at the junction between the upper and reduced section of the tube and the lower and enlarged section of the tube.

A screw 80 is threaded into an opening pro-

vided for that purpose adjacent the upper extremity of base tube 13 and is adapted to engage the upper surface of shoulder 78 formed on seat tube 71 to limit the upward vertical movement thereof.

Secured to the exterior of base tube 13 adjacent the screw 80 is a bracket 81 carrying a spring pin 82 which extends through an opening provided for that purpose in the side wall of base tube 13 to engage in the groove 79 formed in seat tube 71 to lock that tube against movement in either reciprocable direction. It will be understood that when pin 82 is released and tube 71 is telescoped downwardly within tube 13 so that shoulder 78 passes the pin 82, the sole support for seat 10 is the spring 75. In other words, under these circumstances the chair is in condition for bouncing action. In order to hold the pin 82 in its locked position there is provided within the bracket 81 between the bracket and a shoulder formed for that purpose on the pin 82, a spring 83 which urges the pin radially inwardly.

Suitable means is provided for adjusting the foot rest platform 74 vertically of the base tube 13. This means is illustrated in Figure 18. As there shown, the platform 74 is formed with a hub portion 84 which telescopically engages the external surface of tube 13. Threadedly received in an opening provided in a boss portion 85 of the hub is a bolt 86 having a handle 87 at its outer extremity and a clamping element 88 at its inner extremity. By rotating the bolt 86 radially outwardly the clamping element 88 is disengaged from the tube 13 and the platform 74 may be moved to any desired position. When the platform is placed in the desired position it can be securely locked there by rotating the bolt 86 radially inwardly to press the clamping element 88 into firm frictional engagement with the tube 13. By this means suitable adjustment of the platform 74 may be obtained to accommodate it as a foot rest for children of varying weight.

From the foregoing it will be apparent that the present invention provides an extremely novel and useful chair construction which can be used either as a high chair or as a bouncing chair, or simultaneously as both. The chair is safe against harming the child occupant thereof since in the preferred embodiment it is of a pyramid construction which precludes accidentally tipping the chair over. The chair is of simple construction and may be easily assembled and disassembled. In its preferred form it is designed for separation into parts of convenient size for packaging. It is of sturdy and durable construction.

The scope of the invention is indicated in the appended claims.

I claim:

1. A chair including, in combination, a base having an upstanding tube secured thereto, a seat having a downwardly extending tube secured thereto, said seat tube being telescopically received in said base tube for vertical and rotatable movement relative thereto, the seat tube having a portion at its lower extremity of substantially the same outer diameter as the inner diameter of the base tube and having a portion above said first named portion of substantially smaller diameter whereby said last named portion is spaced from the base tube, spring means contained within the tubes for yieldingly supporting the seat from the base, and latch means

associated with said tubes for releasably latching said tubes in predetermined position, said latch means having a portion located within said seat tube and extending outwardly therefrom and adapted to engage the base tube when said tubes are latched in predetermined position.

2. A chair including, in combination, a base having an upstanding tube secured thereto, a seat having a downwardly extending support telescopically received in said tube for vertical movement relative thereto, spring means contained within the tube and engaging said support whereby the seat is yieldingly supported by the base, means adjacent the upper end of said tube engaging a cooperating abutment on said support for limiting the upward movement of said support, and means attached to the lower end of said tube and engaging said spring means for varying the compression of said spring means.

3. A chair including, in combination, a base having an upstanding tube secured thereto, spring means contained within said tube, a seat having a downwardly extending support telescopically received in said tube and engaging said spring means for vertical movement in said tube, said support having weight indicating indicia thereon, an indicator located adjacent said support and adapted to cooperate with said indicia to indicate weight, means on the lower end of said tube engaging said spring means and movable vertically relative to said tube for compressing said spring means, and means rigidly connecting said indicator to said spring compressing means whereby vertical movement of the latter will create vertical movement of said indicator relative to said tube and said support.

HAROLD E. RENAUD.
